MANUFACTURE OF STAPLE FIBER YARNS
FROM CONTINUOUS FILAMENTSWilliam Ivan Taylor and Leslie Brisbane Gibbins,
Spondon, near Derby, England, assignors to
Celanese Corporation of America, a corporation
of DelawareApplication August 25, 1934, Serial No. 741,434
In Great Britain September 5, 1933

3 Claims. (Cl. 19—1)

This invention relates to the conversion of yarns or threads of continuous filaments into yarns having the appearance and characteristics of spun yarns made from staple fibers.

In the production of spun yarns from continuous filaments the continuous filaments may be converted into uniform staple lengths, which are then treated in a manner analogous to that employed with natural staple fiber materials such as wool or cotton. Alternatively a thread or bundle (hereinafter referred to as a "bundle") of continuous filaments may be broken or severed into staple lengths at points which are distributed along the length of the bundle in such a manner that the bundle is not completely severed at any point, but retains to some degree its original continuity, and can then be treated either as a roving or twisted directly into a spun yarn. The staple fibers into which the continuous filaments are converted vary somewhat in length, and this fact is apt to lead to the presence in the final yarn of short fibers which are not long enough to be bound into the yarn and which adhere to or protrude from the surface of the yarn, giving it a hairy or fluffy appearance, and moreover are liable easily to become detached from the yarn or from the fabric into which it is manufactured. It is an object of the present invention to reduce as far as possible the proportion of short fibers in the finished spun yarn.

It has now been found that loose, short fibers can be removed from the continuous product obtained by this latter method, by subjecting such product to the action of a stream of air. According to the present invention, therefore, a bundle of continuous filaments is converted into a continuous product containing staple fibers, and the product is subjected to the action of one or more gaseous streams to remove from such product loose, short fibers, or fibers only lightly held and likely to become detached from the main body thereof. The continuous product thus freed or substantially freed from short, loose fibers is then subjected to a twisting operation, either as the final step or as an intermediate step in the conversion of the product into a spun yarn.

The gaseous stream or streams may be directed against the fibrous product so as to blow away the loose fibers, or may be generated by suction so as to extract or draw the loose fibers out of, and away from, the fibrous product.

A method of converting a bundle of continuous filaments into yarn containing staple fibers, to which the present invention is especially appli-

cable is described in the specification of U. S. application S. No. 726,264 filed May 18, 1934. According to that specification a bundle of continuous filaments is passed over a cutting surface on to which it is lightly pressed so that the surface exerts a cutting action on filaments in the bundle. The cutting surface may take the form of a cutting roller on to which the bundle of filaments is lightly pressed by means of another roller.

In accordance with one embodiment of the invention an air jet may be arranged at any convenient point along the length of the product after the continuous filaments have been converted into staple fibers. More than one air jet may be directed against the product, and in deciding the number of jets to be used, due account should be taken of the strength of the stream to be applied. Thus, if it is only desired to remove the shortest fibers, a relatively feeble blast may be employed and this may be repeated at different positions to ensure the removal of all or substantially all the fibers that it is desired to eliminate.

If any operation is to be performed upon the product which might tend to bind the short lengths of fibers to the product, the air jets should act upon the product before such treatment. Thus for example, where the product is to be treated with an oil or other conditioning fluid which might cause the short lengths of fiber to adhere to the main body of the staple fibers, such conditioning treatment should be carried out after the removal of the short fibers in the manner according to the present invention.

The invention may be employed in conjunction with that described in U. S. application S. No. 734,876 filed July 13, 1934, according to which the hairiness of a spun yarn, due to the presence of abnormally long fibers in the yarn, is overcome by treating the yarn with a material adapted to cause the beard projecting from the surface of the yarn to adhere to the body of the yarn. In this way both the abnormally short and the abnormally long fibers which may be present in the product after its conversion from continuous filaments are dealt with, and a clean yarn substantially free from objectionable beard and fluffiness is produced.

The invention is applicable to the production of spun yarns from continuous filaments generally, e. g. filaments of natural silk or of reconstituted cellulose such as viscose or cuprammonium artificial silk. The invention is, however, of more especial importance in connection with

yarns of cellulose acetate or other organic derivatives of cellulose, since these yarns are not so amenable to the usual operation of "gassing" by means of which fluff and hairiness may be removed, as yarns of cotton, or regenerated cellulose. In addition to cellulose acetate other examples of cellulose derivatives are other cellulose esters, e. g. cellulose formate, propionate and butyrate and cellulose ethers, e. g. ethyl or 10 benzyl cellulose. Mixed yarns consisting of filaments of different materials, e. g. any of those described above may also be employed.

By way of example, some forms of apparatus according to the invention will now be described 15 in greater detail with reference to the accompanying drawing, in which

Fig. 1 is a diagrammatic side elevation of a form of apparatus in which jets of air are directed against the fibrous product, and 20 Figs. 2, 3 and 4 are similar views of forms of apparatus described in U. S. application S. No. 726,264, to which the present invention has been applied.

In Fig. 1, a bundle of continuous filaments 25 passes successively between two pairs of rollers 6, 7, 8, 9 the rollers 8, 9 rotating faster than the rollers 6, 7 so that the filaments are drawn in tension between the two pairs of rollers and caused to break and form a continuous staple 30 fiber product 10, which issues from the rollers 8, 9. In order to remove any unduly short fibers formed by this method, two air nozzles 11, 12 are provided, the nozzle 11 blowing into the nip of the rollers 6, 7 and the nozzle 12 into the nip of 35 the rollers 8, 9. The nozzles 11 and 12 are provided from a common air supply pipe 13, and are preferably of such form as to project a flat stream or blast of air, acting on a substantial length of the staple fiber product. Thus the nozzles 11 and 12 may be in the form of batwing or fish-tail gas burner nozzles.

In Fig. 2, the bundle of continuous filaments 5 passes over a roughened roller 15 having a cutting surface against which it is lightly pressed by 45 means of a roller 16, and then proceeds downwardly to a further pair of rollers 17, 18, the roller 17 being roughened like the cutting roller 15. The rollers 17, 18 grip the filaments and cause them to slip between the rollers 15, 16, whereby filaments in the continuous bundle are severed to form staple fibers. In order to remove 50 short staple fibers formed by this method, three nozzles 20, 21, 22 are provided, fed from a common supply pipe 23 which in turn is supplied from a header 24 serving a number of sets of rollers 15, 16, 17, 18, each dealing with a bundle of continuous filaments 5. A cock 25 is provided to cut off the supply of air from the header 24 to the pipe 23.

In Fig. 3, the bundle 5 is drawn by means of 60 a pair of rollers 17, 18 between a roller 26 and a band 27 having a cutting surface of sand paper, carborundum or other sharp edged material, the band 27 being supported by guide rollers 28. Air nozzles 29 are directed against the staple 65 fiber product 10 formed by the cutting action of the band 27, the nozzles 29 being supplied from the pipe 23 and a header 24.

In Fig. 4, the bundle of continuous filaments 70 5 is drawn by means of rollers 17, 18 between a roughened cutting roller 31 and a pressure member 32 which lightly presses the bundle 5 on to the cutting roller 31. Again, air nozzles 29 are 75 provided, fed from a common supply pipe 23, in

order to blow from the yarn any unduly short staple fibers which may be formed.

It will be understood that while the various air supply pipes and nozzles are described as blowing air at the fibrous material, such apparatus could be adapted to suck air through or past the material to extract short fibers therefrom. The header 24 would thus serve as a suction header, and could conveniently be adapted to conduct the extracted fibers to a suitable receiver.

What we claim and desire to secure by Letters Patent is:—

1. Apparatus for the production of staple fiber 15 yarns, comprising means for converting a bundle of continuous filaments directly into a continuous product containing staple fibers by severing continuous filaments of the bundle, and means for directing a gaseous stream against said product to remove therefrom loose short fibers contained 20 therein.

2. Apparatus for the production of staple fiber 25 yarns, comprising a movable cutting surface, means for causing a bundle of continuous filaments to move over said surface, means for pressing the bundle against the surface, means for causing the surface to move at a speed different from the speed of the bundle and means for directing against the said bundle after passage over the cutting surface a gaseous stream to remove from said bundle short loose fibers contained therein.

3. Apparatus for the production of staple fiber 30 yarns, comprising a rotatable cutting roller, means for causing a bundle of continuous filaments to move over the periphery of said roller, a rotatable roller for pressing the bundle against said cutting roller, means for causing said cutting roller to rotate at a peripheral speed different from the speed of the bundle so that said 40 cutting roller exerts a cutting action on filaments in the bundle, and means for directing against said bundle after passage over the cutting roller a gaseous stream to remove from said bundle short loose fibers contained therein.

4. In a process for the production of yarn containing staple fibers, the steps of converting a bundle of continuous filaments into a continuous product containing staple fibers by severing continuous filaments of the bundle, and concomitantly with such conversion directing a gaseous stream against said product to remove loose 50 short fibers therefrom.

5. In a process for the production of yarn containing staple fibers, the steps of converting a 55 bundle of continuous filaments of cellulose acetate or other organic derivative of cellulose into a continuous product containing staple fibers, by severing continuous filaments of the bundle, and concomitantly with such conversion directing a gaseous stream against said product to remove loose 60 short fibers therefrom.

6. In a process for the production of yarn containing staple fibers, the steps of converting a 65 bundle of continuous filaments into a continuous product containing staple fibers by severing continuous filaments of the bundle, and concomitantly with such conversion directing a gaseous stream against said product to remove loose short fibers therefrom, and twisting and winding said 70 product into yarn.

7. In a process for the production of yarn containing staple fibers, the steps of converting a bundle of continuous filaments into a continuous product containing staple fibers by severing con- 75

tinuous filaments of the bundle, and concomitantly with such conversion directing a plurality of gaseous streams against said product at points along its length to remove loose short fibers from said product.

5. 8. In a process for the production of yarn containing staple fibers, the steps of converting a bundle of continuous filaments into a continuous product containing staple fibers by severing con-

tinuous filaments of the bundle, and concomitantly with such conversion directing a gaseous stream against said product to remove loose short fibers therefrom, and then applying to said product an adhesive material so as to cause beard projecting from the surface of said product to lie down and adhere to the body of said product.
